UNITED STATES PATENT OFFICE

2,590,235

VACUUM CLEANER

George H. Cranmer, Philadelphia, Pa., assignor to Electrolux Corporation, New York, N. Y., a corporation of Delaware

Original application September 22, 1945, Serial No. 618,022, now Patent No. 2,564,467, dated August 14, 1951. Divided and this application November 24, 1950, Serial No. 197,443

6 Claims. (Cl. 183—37)

1

This application is a division of my copending application Serial No. 618,022 filed September 22, 1945 (now Patent 2,564,467 dated August 14, 1951), and relates back thereto for all common subject matter.

One of the objects of my invention is to provide an improved seal for the inlet opening of a vacuum cleaner dust bag, and more particularly to provide a seal of this type for use with dust bags which are intended to be thrown away when filled.

One of the advantages of the seal in accordance with my invention is that it offers no resistance whatsoever to the passage of dirt-laden air into the bag during use.

Another advantage is that, upon removal of the bag from the vacuum cleaner, the seal automatically closes the inlet opening without interference from the dust and dirt contained in the bag.

Further objects and advantages of my invention will be apparent from the following description considered in connection with the accompanying drawings, of which:

Fig. 1 is a horizontal cross-sectional view of a vacuum cleaner embodying my invention;

Fig. 2 is a front view of the dust container shown in Fig. 1;

Fig. 3 is a cross-sectional view taken on the line 3—3 of Fig. 2;

Fig. 4 is an end view of the inside of a cover member forming part of the cleaner shown in Fig. 1;

Fig. 5 is a cross-sectional view taken on the line 5—5 of Fig. 4;

Fig. 6 is a front view showing an alternative form of dust container which may be used with the cleaner shown in Fig. 1; and

Fig. 7 is a view similar to Fig. 6, but with a valve member in open position.

Referring more particularly to Fig. 1, reference character 10 designates the casing of a tank type vacuum cleaner. The casing 10 is provided at one end with a cap 60 having an exhaust opening 62. A motor fan unit 98 is fixed within the casing by means of a suitable support 100 which provides an air tight seal between the casing and the motor fan unit.

A cylindrical member 130 is arranged to extend between the fan housing 132 and the casing 10 with its right end bearing against and being centered by the support 100. The opposite end of this cylindrical member is formed with an inwardly extending flange 134 which bounds an opening which is preferably larger than the inlet to the fan housing. A compression spring 136 has one end secured to flange 134 in any suit-

able manner, while the other end of the spring is secured to an annular disc 138. This disc is connected by spaced members 140 to another disc 142 which is secured to a ring 144. The ring is secured within the open end of a cylinder 146, the outer diameter of this cylinder being slightly less than the inner diameter of casing 10 so that the former may easily slide within the latter. The length of the cylinder should be sufficient to prevent it from tilting and binding within the casing. If desired a wire mesh screen or the like 148 may be carried by the annular disc 142 and a similar screen 150, but preferably of finer mesh may be carried by the disc 138. A ring 151 is removably secured in the left end of casing 10 and acts as a stop for cylinder 146 when the latter is moved to the left by spring 136.

A lever 152 is pivotally mounted on a suitable bracket 154 extending outwardly from one side 20 of the casing 10. One end of the lever is formed with a latch 156 which extends through an opening formed in the side of casing 10. The right edge of latch 156 is normal to the casing wall while the end edge of the latch is beveled. A 25 compression spring 158 is disposed between the lever 152 and the casing so as to tend to pivot the lever in counterclockwise direction to thus move the latch 156 into the casing. The opposite end of the lever is provided with a manually engageable portion such as the button 160. This end of the lever overlies one end of a lever 162 which is pivoted on a suitable bracket 164. A compression spring 166 is disposed between the side of the casing and lever 162, while the opposite end of 30 this lever is provided with a latch 168 which serves to retain a front end cover 170 in closed position. A ring 172 is secured to the outside of casing 10 and the cover 170 is pivotally connected to this ring by means of a hinge 174. Included in 35 the hinge structure is a spring 176 which tends to pivot the cover to open position. A cover plate 177 is provided for concealing the major portions of levers 152 and 162.

The construction of the inner face of the cover 45 170 is shown more in detail in Figs. 4 and 5. As there shown, the cover is formed with an annular ring 178 at its periphery and with a tubular projection 180 extending inwardly from the hose coupling 182. A small projection 184 is provided a 50 short distance radially outwardly from the tubular projection 180. Opposite the hinge 174 the outer face of the cover is formed with a recess 186 which is engaged by the latch 168.

The dust container 20 includes a bag portion 55 22, preferably of porous paper, secured to a circular disc 24, the outer diameter of which is such that it will be received in an annular seat formed

in the ring 172 and clamped in place by the annular projection 178 on the cover 170 when the latter is closed. The disc 24 is formed with a central aperture 30 into which the tubular extension 180 extends.

The arrangement for closing the opening 30 when the bag is to be ejected from the cleaner is shown more particularly in Figs. 2 and 3. Suitably secured to the outer face of the disc 24 is a pair of parallel guide rails 188. A generally rectangular plate 190 is slidably supported by the guide rails and is formed with an aperture 192 therethrough at least as large, and preferably a little larger, than the aperture 30 in the disc 24. Plate 190 is provided with projections 194, while similar projections 196 extend upwardly from the guide rails 188. A rubber band or the like 198 is looped around the projections 194 and 196 and consequently tends to move the plate 190 to the right, as viewed in Fig. 2. Prior to the introduction of the bag into the casing the plate 190 is retained in the position shown in Fig. 2 by means of a projection 200 struck up from the material of the disc 24. This projection is so positioned as to be contacted by the projection 184 on the front cover when the latter is closed so as to force the projection 200 out of the path of travel of the plate 190. In order to assure that the dust container will be placed in the casing in the proper position so that these two projections will be in alignment, the disc 24 is preferably formed with a notch 202 into which extends a similar shaped projection formed in the annular seat of ring 172. The distance from the left end edge of the plate 190 to the aperture 192 is greater than the diameter of the aperture 30 in the disc 24 so that, when the plate 190 is moved to the right under the action of the rubber band 198 the aperture 30 will be completely closed.

The above described device operates as follows:

After a dust container has been ejected from the cleaner in a manner to be described herein-after, the spring 136 has moved the cylinder 146 to the left, as viewed in Fig. 1, until the left end of the cylinder strikes the internal ring 151 at the end of the casing 10. When it is desired to insert a new dust container, the operator most conveniently stands the cleaner on end and presses against the screen 148 so as to force the cylinder 146 towards the exhaust end of the cleaner, thus compressing spring 136. As soon as the left end of the cylinder 146 passes the latch 156, the spring 158 pivots the lever 152 in counter-clockwise direction so as to project the latch 156 inwardly to thus retain the cylinder in this position. Thereafter, the dust container 29 is introduced into the open end of the casing and the notch 202 in the periphery of the disc 24 is lined up with the corresponding projection on the ring 172. Thereupon, the cover 170 is pivoted to closed position. During closure of the cover the edge thereof strikes the beveled surface of the latch 168 and pivots the arm 162 in counter-clockwise direction so that the latch may snap into the recess 186 in the cover to hold the cover closed. However, this pivoting of the lever 162 does not cause any pivoting of the lever 152 and hence, the cylinder 146 is not released. When the cover is closed the projection 184 thereon strikes the projection 200 on the disc 24 so as to force the projection 200 out of the path of travel of the valve plate 190. However, the plate cannot be moved to closed position by

the rubber band 198 because the tubular extension 180 on the front end cover extends through the aperture 192 in the valve plate, and also because the projection 184 on the cover is now located in the path of travel of the plate.

During cleaning, dust-laden air is drawn in through the hose coupling 182 and passes through the tubular extension 180 to the interior of the dust container 20. The air passes through 10 the porous material of the bag portion 22 to the inlet of the fan and is finally discharged through the exhaust opening 62, the dust being retained in the dust container.

When it is desired to remove the bag the motor 15 is shut off and pressure is applied to the button 160. This causes the lever 152 to pivot in a clockwise direction, which in turn causes the lever 162 to pivot in a counter-clockwise direction. The relative lengths of the lever arms and the 20 location of their pivot points are such that the latch 168 releases the cover 170 before the latch 156 releases the cylinder 146. As soon as the cover is released, the spring 176 pivots it to open position. When the tubular projection 180 has 25 been withdrawn from the opening 182 in the valve plate 190 and the projection 184 has been moved out of the path of travel of this plate by the opening of the cover, the rubber band 198 quickly moves the plate to the right as viewed in 30 Fig. 2, so as to seal the aperture 30 in the disc 24. An instant after the cover is opened the latch 156 releases the cylinder 146, whereupon the latter is moved suddenly to the left by the energy stored in the compressed spring 136 so 35 as to force the sealed dust container out of casing 10.

If desired, the guide rails 188 and the valve disc 190 may be made of metal, but due to the fact that it is necessary for this valve to operate 40 only once, these parts may be made of cardboard or any other relatively cheap and fairly stiff material so as to maintain the cost of the disposable dust container at a minimum.

If it is desired to open the cover 170 without 45 having the bag ejected, this may be done by inserting a finger into the recess 186 and exerting force against the latch 168 to pivot the lever 162 counter-clockwise. This does not cause pivoting of the lever 152 and hence the cylinder 50 146 is not released.

In Figs. 6 and 7 there is shown a dust container, suitable for use in the vacuum cleaner illustrated in Fig. 2, and differing from the container shown in Figs. 2 and 3 in the construction of the valve 55 for closing the inlet 30 to the container. This dust container includes a circular disc 24 preferably made of cardboard and formed with a centrally located aperture 30. Fixed to the front of the disc 24 by means of rivets or the like 204, or 60 by adhesive, is a valve guide member 206 which is spaced from the disc by the thickness of a flat member 203. A valve plate 210 is pivotally mounted on the disc 24 at 212 and has the configuration best illustrated in Fig. 7. The thickness 65 of the plate 212 is preferably slightly less than that of the member 206 so that the valve plate may move without binding between the disc 24 and the guide 206. A spring member, such as the rubber band 214, is connected between the pivotal valve plate and the fixed guide member, or any other fixed point on the disc 24, and tends 70 to pivot the plate in clockwise direction from the open position shown in Fig. 7 to the closed position illustrated in Fig. 6. In the latter position the edges 216 and 218 of the valve plate abut

against the edges of the member 208 so as to limit movement of the plate under the action of the rubber band.

A displaceable abutment 220, which may be similar to the projection or abutment 200 shown in Fig. 2, is struck up from the surface of the disc 24 and serves to retain the valve plate in open position prior to placing the dust container in the vacuum cleaner. As was described in connection with Figs. 2 through 5, when the front end cover 170 is closed, a projection 184 thereon strikes the struck up projection 220 and forces it down flush with the surface of the disc 24. The valve plate 212 is still retained in open position, however, by its striking either the tubular extension 180 or the projection 184 on the front end cover as long as the cover remains closed. When the cover is opened, the valve plate is free to pivot clockwise under the action of the rubber band and consequently closes the aperture 20. It will be noted that the lower end of the valve member passes under the lower end of the guide 206 and hence is prevented from accidentally bending away from the disc 24.

If desired, the valve plate may be provided with a finger hole 222 whereby it may be initially pivoted to the open position. However, this will ordinarily be done at the time the bag is manufactured and the valve plate will remain open prior to its introduction into the cleaner and during the use of the container in the cleaner and will be closed only when the front cover is opened. Particularly in view of the fact that normally this valve has to operate only once, all of the parts may be made of cardboard or other relatively cheap material.

This bag is used in the cleaner shown in Fig. 1 in the same manner as is the bag illustrated in Figs. 2 and 3, and therefore a detailed description of the operation of the cleaner in conjunction with this bag is unnecessary.

While I have shown and described several more or less specific embodiments of my invention it is to be understood that this has been done for purposes of illustration only, and that the spirit or scope of my invention is not to be limited but is to be determined from the appended claims. Furthermore, while I have shown my invention as embodied in a vacuum cleaner having means for ejecting the dust bag therefrom, it is clear that it could be used as well in an ordinary vacuum cleaner not having this ejection feature.

What I claim is:

1. In a vacuum cleaner, a casing having an opening, a cover for closing said opening, a dust bag insertable into and removable from said container through said opening, means for producing flow of air through said casing and through the dust bag therein, said dust bag having an aperture through which the air enters the bag, a valve member on said bag for closing said aperture, means biasing said valve member towards closed position, a displaceable abutment on said bag for holding said valve member in open position, and means on said cover for displacing said abutment out of valve holding position when the cover is closed and for holding said valve member open until the cover is opened.

2. In a vacuum cleaner, a casing having an opening, a cover for closing said opening, a dust bag insertable into and removable from said container through said opening, means for producing flow of air through said casing and through the dust bag therein, said dust bag having an aperture through which the air enters the

bag, a valve plate pivotally mounted on said bag for closing said aperture, resilient means biasing said valve plate towards closed position, a displaceable abutment on said bag for holding said valve plate in open position, and a projection on said cover for displacing said abutment out of valve holding position when the cover is closed and for holding said valve plate open until the cover is opened.

10 3. In a vacuum cleaner, a casing having an opening, a cover for closing said opening, a dust bag insertable into and removable from said container through said opening, means for producing flow of air through said casing and through the dust bag therein, said dust bag including a substantially flat disc across the mouth of the bag formed with an aperture through which air enters the bag, a pair of guide rails on said disc disposed on either side of said aperture, a valve plate slidably supported by said rails for closing said aperture, resilient means for biasing said valve plate towards closed position, a displaceable abutment on said disc for holding said valve plate in open position, and a projection on said cover for displacing said abutment when the cover is closed and for holding said valve plate in open position until the cover is opened.

15 4. A dust separating and containing member for a vacuum cleaner including, a disc formed with an inlet opening, a bag of filter material secured to said disc, a valve member on said disc for closing said opening, means for biasing said valve towards closed position, and a displaceable tab struck out of said disc for retaining said valve member in open position.

20 5. A dust separating and containing member for a vacuum cleaner including, a disc formed with an inlet opening, a bag of filter material secured to said disc, a pair of guide rails on said disc disposed on either side of said opening, a valve plate slidably supported by said rails for closing said opening, resilient means for biasing said valve plate towards closed position, and a displaceable abutment on said disc for retaining said valve plate in open position.

25 6. A dust separating and containing member for a vacuum cleaner including, a disc formed with an inlet opening, a bag of filter material secured to said disc, a valve plate pivotally mounted on said disc for closing said opening, resilient means for biasing said valve plate towards closed position, and a displaceable tab struck out of said disc for retaining said valve plate in open position.

30 GEORGE H. CRANMER.
